Primary Examiner—Cathy Anne MacCormac
Attorney, Agent, or Firm—Eric Fincham[57] **CLAIM**

An ornamental design for a combined litter box and sifting cover for felines, as shown and described.

DESCRIPTION

FIG. 1 is an exploded perspective view of a combined litter box and sifting cover for felines showing my new design;

FIG. 2 is a top view thereof;

FIG. 3 is a bottom view thereof;

FIG. 4 is a front view thereof;

FIG. 5 is a side view thereof, the opposite side being a mirror image of the side shown; and,

FIG. 6 is a rear elevational view thereof.
